SPECIFICATION forming part of Design No. 24,492, dated July 16, 1895.

Application filed June 8, 1895. Serial No. 552,177. Term of patent 3½ years.

To all whom it may concern:

Be it known that I, ARTHUR MIDDLETON ROSE, residing at Yonkers, county of Westchester, State of New York, have invented and produced a new and original Design for a pattern to be wrought into Wilton and other Carpetings in such coloring as may be designed; and I do hereby declare that the drawing accompanying this specification gives and conveys to any one skilled in the art of carpet weaving and manufacture a clear understanding of the same, and is sufficient to enable such person to use my invention.

The design consists of the body A and the border B.

The body A is decorated with leaves of the chrysanthemum appearing on a plain background, with flowers of the same plant appearing at intervals.

The border B is decorated principally with

a vine-like grouping of chrysanthemum flowers and leaves running longitudinally through the center and showing a broad band of background on each side. The inner edge of border shows a narrow wavy band and the outer ²⁵ edge a sub-border of scrolls.

What I claim as my invention, and desire to secure by Letters Patent, is—

1. In a design for a carpet, the body A, substantially as shown.
2. In a design for a carpet, the border B, substantially as shown.
3. The design for carpets, consisting of the body A, and the border B, substantially as shown.
